US00D986719S

(12) **United States Design Patent** (10) **Patent No.:** **US D986,719 S**
(45) **Date of Patent:** **** May 23, 2023**

(54) **HOOK**

(71) Applicant: **Shenzhen Aichong Industry Co., Ltd,**
Shenzhen (CN)

(72) Inventor: **Aicheng Yin, Changning (CN)**

(**) Term: **15 Years**

(21) Appl. No.: **29/886,121**

(22) Filed: **Mar. 6, 2023**

(51) **LOC (14) Cl.** **08-11**

(52) **U.S. Cl.**
USPC **D8/367**

(58) **Field of Classification Search**

USPC D8/367, 354, 349, 373; D6/323
CPC A47G 1/00; A47G 25/00; A47G 25/0614;
B25H 3/04; B25H 3/06; B25H 3/003

(57) **CLAIM**

The ornamental design for a hook, as shown and described.

DESCRIPTION

FIG. 1 is a perspective view of a hook showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view of a hook as shown;

FIG. 9 is another perspective view thereof shown in an alternative configuration of use; and,

FIG. 10 is another perspective view thereof, shown in a second alternative configuration of use.

The broken lines depict portions of the hook and form no part of the claimed design.

1 Claim, 10 Drawing Sheets
